UNITED STATES PATENT OFFICE

PAUL LUX AND FREDERICK LUX, OF WATERBURY, CONNECTICUT, ASSIGNEES TO LUX
CLOCK MANUFACTURING COMPANY, OF WATERBURY, CONNECTICUT, A CORPORA-
TION OF CONNECTICUT

DESIGN FOR A PYRAMID CLOCK CASE

Application filed June 27, 1929. Serial No. 31,853. Term of patent 7 years.

To all whom it may concern:

Be it known that we, PAUL LUX and FRED-
ERICK LUX, citizens of the United States, re-
siding at Waterbury, county of New Haven,
and State of Connecticut, have invented a new,
original, and ornamental Design for a Pyr-
amid Clock Case, of which the following is a
specification, reference being has to the ac-
companying drawing, forming part thereof.

Fig. 1 is a front view of a pyramid clock
case, showing our new design.

Fig. 2 is a side view of the same.

We claim:

The ornamental design for a pyramid clock
case as shown.

In testimony whereof, we have affixed our
signatures to this specification.

FREDERICK LUX.
